(57) CLAIM

The ornamental design for a shredder pin, as shown and described.

DESCRIPTION

FIG. 1 is a perspective view of the shredder pin of the present invention, looking angularly towards a back end thereof;

FIG. 2 is a side elevational view of the shredder pin of the present invention, which side view is common to all sides of said design;

FIG. 3 is a top end or plan view of the shredder pin of the present invention; and,

FIG. 4 is a view of the bottom or back end of the shredder pin of the present invention.
